UNITED STATES PATENT OFFICE.

SAMUEL W. RUSHMORE, OF PLAINFIELD, NEW JERSEY.

RADIATOR FOR COOLING FLUIDS.

Application filed December 6, 1921. Serial No. 520,209.

To all whom it may concern:

Be it known that I, SAMUEL W. RUSHMORE, a citizen of the United States, and resident of Plainfield, in the county of Union and State of New Jersey, have invented certain new and useful Improvements in Radiators for Cooling Fluids, of which the following is a specification.

My present invention relates to radiators, particularly radiators for use with cooling systems of the type which operate by the boiling and condensing cycle for the cooling of automotive engines, on the principle described in my Patent No. 1,378,724, granted May 17, 1921. In such system the water and steam from the engine jacket is discharged into a separating chamber in the bottom of the radiator, the water being returned to the engine jacket and the steam rising into the air-cooled passages of the radiator, so that the radiator operates as an up-flow condenser, the condensate returning by gravity against the upward flow of steam.

In said patent this method is referred to as applicable to radiators of the types which are now employed as standard equipment on automobiles, trucks, etc., but such radiators are primarily designed for cooling of water instead of steam, by down-flow instead of up-flow, and I have discovered that in the practical operation of such radiators by the "steam cooling" system, the potential cooling capacity is not properly utilized.

The primary difficulty is that the fan which draws the cooling air through the radiator, induces a much heavier blast in the central portions of the condensing area than at the sides. Consequently the central portions are capable of radiating much more heat and condensing much more steam per unit of cooling surface, than are the sides. But the side passages which are least cool are designed to have the same, or less, flow resistance than the central portions, with the result that where the relatively frictionless, massless steam is substituted for water, the balance between the several up and down passages, as regards flow capacity and condensation capacity, is completely upset.

Careful experiment shows that long before the total volume of steam to be condensed becomes great enough to tax the cooling capacity of the radiator as a whole, the inferior cooling capacity at the sides will be over-taxed. The heat therefore creeps

higher up, heating the side portions; the air becomes lighter so that the hot air and steam rise into the empty space at the top of the radiator displacing the colder air downward (because the colder air is heavier and because air, even at 212° F., is about 60% heavier than steam); but the same or even greater volume of steam flowing directly up into the better-cooled central portions is condensed long before it reaches the top, the passages and air above it being kept cold by the fan. The up-flowing steam can push the air upward only the limited height to which such steam rises before being condensed.

As a result there remains in the central portion of the radiator a body of air which is supported from below by up-flowing steam and sealed in above by steam rising from the sides. Reverse curl or eddying of such steam from the sides may serve to scavenge out more or less of the air in the relatively open space above the honeycomb, but has practically no effect on the air trapped and kept cold in the narrow central passages of the radiator. Hence the air thus trapped stays trapped, practically excluding the steam which might otherwise flow in from both top and bottom.

While this objectionable action may be more readily analyzed and understood in connection with radiators of the type in which the steam passages are parallel vertical conduits having no cross flow connections except at top and bottom, nevertheless, the same action is found to occur to an undesirable extent in radiators of the type in which the honeycomb is built up from a multiplicity of short horizontal tubes forming an interconnected net-work of passages.

In its broadest aspects, my invention includes proportioning and arranging the steam condensing passages with reference to the different portions of the area of the radiator so that the steam will flow through all of the condenser passages at rates which will insure driving the contained air to a point suitable for its collection and discharge instead of trapping it.

The preferred point for collection and discharge of the air is the upper space in the radiator above the top of the condensing passages. To drive it there I arrange matters so that steam will not reach the well cooled central portions of the radiator ex-

cept from below. There are many factors, one or more of which may be varied separately or together to bring about this result.

- 5 The up-flow paths at the sides may have their flow capacity decreased. This may be accomplished by making them longer, or of smaller cross-section, or arranging them so that the flowing steam will be checked by 10 a succession of high-angled impacts, all of which factors are utilized in the device of my prior application, Serial Number 500, 382, filed September 13, 1921. The decrease of flow section and the obstruction by impact may be distributed from bottom to top 15 of the side passages, as in said application, or may be localized at desired points.

Where, as in this present application, the radiator has a "honeycomb" formed of a 20 multiplicity of short horizontal tubes, affording a multiplicity of cross-connections for lateral distribution of the steam, two ways are shown.

One way involves decreasing the cross section of the steam flow passages at the sides, 25 preferably by making the tubes the same in number per unit of front area but of much larger sizes for the sides than for the central portion. This has the desired effect of increasing the resistance, thereby decreasing the steam flow at the sides. At the same time, it has the separate and distinct advantages of increasing the cooling surface to which such flow is exposed and of increasing 30 the induced flow of air in those portions of the honeycomb which are out of the direct path of the fan blast. This feature is a distinct advantage even where the radiator is used for water-cooling in the usual way, instead of for my preferred steam-condensing method.

The above and other features of my invention will be more fully understood from the following description in connection with 45 the drawings, in which—

Fig. 1 is a front elevation indicating the relations and relative sizes of the air passages in one type of radiator constructed in accordance with my present invention.

50 Figs. 2 and 3 are sectional detailed views showing the proportions and relations of four adjacent tubes in two different groups taken respectively from the sides and from the center of the honeycomb on the dotted lines 2—2 and 3—3, respectively.

It will be understood that Fig. 1 is on a reduced scale; that the scale for Figs. 2 and 3 is somewhat larger; and that the scale for Figs. 4 and 5 is still larger.

60 Figs. 4 and 5 are practically full size end views of two of the sizes of tubes employed.

Fig. 6 is a diagrammatic vertical section intermediate the front and rear faces of a cross tube radiator which embodies another 65 form of my invention.

Fig. 7 is a horizontal section on the line 7—7, of Fig. 6.

Fig. 8 is a detailed perspective view of one of the deflectors shown in Fig. 6.

It will be understood that the radiators as 70 shown in these drawings are of the air cooled type, and adapted for use in combination with the motor, water supply system, pump and fan commonly employed on automotive vehicles. They may be, and preferably are, units adapted to be substituted for the radiator 4, in the combination of parts 75 shown in Fig. 1 of my above-mentioned patent; but they may be employed, with or without modifications, wherever an equal, 80 flow, up-flow, or air scavenging condenser is desired.

In Fig. 1 of the present drawings, the radiator, here used as a condenser, comprises the separating chamber 1 into which the steam or hot water and steam from the engine is discharged through pipe 2. The water, including condensate, flows out of 85 said space through pipe 3, preferably drawn by a pump which is preferably a force pump 90 and may be a gear pump, as shown in my said patent.

Above the separating chamber 1, the radiator is a honeycomb portion formed of a 95 multiplicity of closely-set transverse tubes through which tubes the cooling air draft is drawn by the fan and in the interspaces between which flows the steam to be condensed. These interspaces terminate in the empty 100 space 5 in the top of the radiator. There may be an over-flow pipe 13 through which air may "breathe" in and out, according as the volume of steam supplied from below increases and decreases. There is usually also 105 the filler cap 14 through which air inevitably enters, when fresh water is supplied to replace losses. The in and out flow of air may be modified to some extent if breather valves such as shown in Fig. 6 of my said patent 110 are employed, but they will not prevent air inlet and outlet, hence the entire interior of the radiator must be considered as initially, and frequently, air-filled.

The tubes constituting the honeycomb are 115 shown as having body portions 6 which are expanded at the ends to form hexagonal enlargements 7. The tubes are all of the same length and may be, say 2 $\frac{1}{2}$ or 3 inches long, and the hexagonal enlargements are all of 120 the same diameter and may be, say $\frac{3}{8}$ inch in diameter. In the form shown in Figs. 6 and 7, the body portions 6 are shown as being also of the same diameter, but in Figs. 1 to 5, said body portions are shown as of three different sizes, varying from say $\frac{5}{16}$ inch or less, for the size shown in Figs. 3 and 5, to say $\frac{7}{16}$ inch for size shown in Figs. 2 and 4.

125 While the actual size may vary quite widely, it will be evident from the above that the maximum cross section for flow of 130

air through the tubes may be appreciably greater for the side tubes than for the central tubes, while the interspaces 3, as indicated in Figs. 2 and 3, may be much smaller for the side tubes than for the central tubes. As shown in the drawings, the tubes 4^a, having the small diameter bodies and large interspaces, comprise the seven middle rows; the next larger size tubes 4; the next three rows on either side of the center, while the tubes 4^b, having the largest body portions and the smallest interspaces, comprise the last three rows adjacent each side of the radiator.

Obviously more sizes of tubes could be employed up to the limit where the center row is the smallest, and the successive rows on either side thereof are progressively larger from the center to the sides, but in practice, three well selected sizes are sufficient for the purpose.

From my full explanation of the principles of the invention, it will be understood that the tubes 4^b, 4^a, at the sides are so large and have such small interspaces that the flow capacity of the interspaces will be small as compared with the flow capacities of the central interspaces, for the purpose and with the result that when steam is evolved in sufficient quantities to penetrate to the top of the honeycomb through the side interspaces, the resistance to such flow will build up a back-pressure sufficient to supply the large amount of steam required at the central portions to utilize the great cooling capacity at the center and in addition to lift the body of cold air in the upper central portions.

It will be understood that in this form of radiator, the interspaces for flow of steam constitute an interconnected net work and that the higher resistances at the sides due to the large tubes 4^b, and to the next larger tubes 4, will have the effect of deflecting steam from the center toward the sides so that in this case cross flow from the sides and up-flow from the center co-operate to break up and expel the body of cold air in the upper central portion, which would otherwise be trapped by steam rushing up at the sides and curling back through the empty space 5.

In the modification shown in Figs. 6, 7, and 8, the honeycomb is of the same construction as above-described, but the tubes 4 all have their body portions of the same diameter. In this case the resistance to up-flow of steam at the sides and partial deflection thereof toward the center, is affected by means of obstructions or deflectors at the sides. As shown in the drawings, these consist of sheet metal obstructions 15, which are preferably widest so as to afford the greatest obstruction nearest the sides of the radiator; and they are preferably narrowed

toward the center. They lie between and next upon the body portions of tubes 4, but they may be soldered or otherwise secured to the side walls 8, if desired.

In the form shown in Figs. 6, 7, and 8, the obstructing device 15 is shown as arranged at or near the level of the center of the fan and there is another similar obstruction 15^a arranged at a considerably lower level and extending a considerably shorter distance toward the center. It will be obvious, however, that the number, widths, taper, and direction of the obstructions may be widely varied, keeping in mind the principle of my present invention and the purpose to be served by the obstructions.

I may insert a central baffle plate such as 15^b to so restrict the cross section of the steam flow area that the velocity of the steam will be increased so that the contained air will be swept along ahead of the steam and into the upper space of the radiator.

As is common with radiators of this type, the honeycomb may be built up by assembling the tubes in any suitable support, and soldering or brazing the enlarged ends by dipping in molten tin or lead. The body portion or shell of the radiator comprises the usual peripheral wall and the front and rear walls above and below the honeycomb. The thickness of the radiator is approximately the same as the length of the tubes, but the height of the radiator is preferably such as to leave the above-described space 5 at the top.

It will be recognized that the form shown in Figs. 1 to 5 hereof is distinguishable from the form shown in Figs. 6 to 8, for the reason, among other things, that in Fig. 1 two factors are brought into play for bringing about the desired result, first, the expedient of decreasing flow capacity at the sides and, second, the expedient of increasing cooling area at the sides. While both expedients are combined in the radiator shown and while there are advantages in so combining them, theoretically the desired measure of control could be had by use of either one of these expedients without the other.

While a hexagonal shape is more desirable for the ends of the cross-tubes, as requiring less deformation and expansion of the ends of the tubes, nevertheless, so far as concerns the main functional features of my invention, either the ends or the body portions might be squares or equilateral triangles.

I claim:

- An air cooled radiator having a multiplicity of front-to-rear passages for through flow of the cooling air, the walls defining said passages being spaced apart to afford interspaces for flow of fluid medium to be cooled therein, said air passages being of larger flow section for the sides than for the central portions of the radiator.

2. An air cooled radiator having a multiplicity of front-to-rear passages for through flow of the cooling air, the walls defining said passages being spaced apart to afford interspaces for flow of fluid medium to be cooled therein, said interspaces being of greater flow-section for the central than for the side portions of the radiator.
3. A radiator as specified in claim 1 with the further feature that the air passages are arranged in successive vertical rows, with the vertical distances between the axes of adjacent passages in the same row substantially the same for all rows regardless of the diameters of the tubes comprising the rows.
4. A radiator as specified in claim 1 with the further feature that the number of air passages per unit area is the same for all parts of the area.
5. A radiator having a honeycomb and a chamber below the honeycomb, the honeycomb comprising short horizontal tubes having enlarged hexagonal ends assembled in parallel relation with the said hexagonal ends interfitting, the hexagonal ends being all of substantially the same diameter and the intermediate body portions of the tubes being of smaller diameter for the central tubes than for those nearer the sides.
6. A radiator of the variable-duty, fan-cooled type, of large front area and relatively thin from front to rear, comprising a lower chamber, an upper chamber and an intermediate portion traversed by a multiplicity of short, open-ended front-to-rear tubes for through draft of the cooling air and affording between them, interiorly of the radiator, a multiplicity of up-and-down cross-communicating paths of different cooling capacities or rates, for flow of fluid between said lower and upper chambers; means for supplying steam or vapor in said lower chamber and withdrawing condensate therefrom; and means for permitting escape of air from said upper chamber in response to the internal pressure changes attendant upon use of the device; the interior paths of less condensing capacity being arranged to have greater flow resistance than those of greater condensing capacity.
7. A radiator of the variable-duty, fan-cooled type, of large front area and relatively thin from front to rear, comprising a lower chamber, an upper chamber and an intermediate portion traversed by a multiplicity of short, open-ended front-to-rear tubes for through draft of the cooling draft and affording between them, interiorly of the radiator, a multiplicity of up-and-down cross-communicating paths of different cooling capacities or rates, for flow of fluid between said lower and upper chambers; means for supplying steam or vapor in said lower chamber and withdrawing condensate therefrom; means for permitting escape of air from said upper chamber in response to the internal pressure changes attendant upon use of the device; in combination with baffles or deflectors for causing flow of the steam or vapor toward the better cooled central portions of the radiator.

Signed at New York in the county of New York and State of New York this 5th day of December A. D. 1921.

SAMUEL W. RUSHMORE,
